UNITED STATES PATENT OFFICE

156,821

RADIO CABINET

Kurt Emde, Itasca, Ill., assignor to Zenith Radio Corporation, a corporation of Illinois

Application January 16, 1948, Serial No. 143,839

Term of patent 7 years

(Cl. D56—4)

To all whom it may concern:

Be it known that I, Kurt Emde, citizen of the United States, and resident of Itasca, in the county of Cook, State of Illinois, have invented a new, original, and ornamental Design for a Radio Cabinet, of which the following is a specification, reference being made to the accompanying drawing, forming a part thereof.

Fig. 1 is a perspective view of a radio cabinet, showing my new design.

Figure 2 is a sectional view taken along lines 2—2 of Fig. 1.

Figure 3 is a sectional view taken along lines 3—3 of Fig. 1.

The rear is plain and the other side is the same as the side shown.

I claim:

The ornamental design for a radio cabinet, as shown and described.

KURT EMDE.
